UNITED STATES PATENT OFFICE.

RANDOLPH S. FOSTER, OF SING SING, NEW YORK, ASSIGNOR TO HIMSELF,
C. WALSH, AND J. C. NOBLES.

IMPROVEMENT IN LOCKS.

Specification forming part of Letters Patent No. 40,077, dated September 22, 1863.

To all whom it may concern:

Be it known that I, RANDOLPH S. FOSTER, of Sing Sing, in the County of Westchester and State of New York, have invented certain new and useful Improvements in a Combined Lock, Knob-Catch, and Night-Latch; and I do hereby declare that the following is a full, clear, and exact description of the construction and operation of the same, reference being had to the accompanying drawings, making a part of this specification, in which—

Figure 1 represents a perspective view of the lock, &c. Fig. 2 represents a vertical longitudinal section of the same. Fig. 3 represents a detached part of a portion of the interior of the lock not distinctly seen in Fig. 2. Fig. 4 represents the key of the lock, knob-catch, and night-latch. Fig. 5 represents the knob and its shank. Fig. 6 represents the tumblers detached from the case.

Similar letters of reference, where they occur in the separate figures, denote like parts in all cases.

The lock is represented as a mortise-lock, in which A is the case, B the face-plate, and C the bolt, which, for the purpose of lock, catch, and night-latch, is made with a bevel, D, so as to run back into the case when drawn against the keeper.

The tumblers E are shown separately at Fig. 6, and when piled up in the lock are kept in their vertical movements by guide-pins $a a' a''$, permanently set in the lock-case. The tumblers E have six openings or slots in them—viz., $b c d e f g$ —of which b are simply guide-slots which allow the tumblers to move past the guide-pin a . The others, however, must all be arranged or disarranged, as circumstances may require in locking, unlocking, or shooting the bolt by the key or by the knob.

F is a cam-wheel having a hub, h , that projects through the side plate of the case, and through this hub and wheel are cut the openings for the key G, which has bits 1 2 3 4 5 on opposite sides of the shank thereof, one set of bits projecting farther from the shank than the other set. Upon the inside of this cam-wheel F, or the side opposite to that from the hub h , there is a projecting piece, i , which is slotted, so as to allow the long bits of the key to pass through, while a long slot, j , in the key-bits admits the solid or uncut portion

of this projecting piece i . There is also upon this cam-wheel F an arm, k , which has a projecting stud or pin, l , in it, and a second arm, m , the objects and purposes of which will be presently explained.

The bolt c is guided in its movements by the pins $a' a''$. It has a shoulder, n , against which the arm m on the cam-wheel F takes under circumstances, as also a shoulder, o , against which the stud or pin l in the arm k takes under certain other circumstances. There is also a projecting piece, p , on the rear end of the bolt, against which the arm H (that is upon the hub I , through which the shank J of the knob K passes) takes, to move back the bolt when simply used as a knob-bolt or catch, and the bolt when not otherwise controlled is forced out of the lock by a spring, x , behind it.

The shank J of the knob K is divided at or near its center, as at r , the portion s being fast to and turning with the knob, while the portion t is loose thereon, so that while the knob K and portion s would operate the hub I and arm H , and consequently the bolt C , yet a knob on the other end of the shank would not do so, as it would only turn the part t upon the interior, which is really the shank, the outer portion being only a loose sleeve turning upon the inner portion.

The bolt c is represented in Fig. 2 as being thrown out to its full extent and locked out by its stud u , which bears against a solid portion of the tumblers E, and in this position it is a lock to the door, and can only be unlocked by the key G, which is inserted in the key-slot, and by the turning of which the tumblers are so arranged as that the slots e shall all come in line so that the pin l on the arm k may traverse them, and so that also the openings f may all come in line, that the stud u on the bolt may pass through them. When the slots or openings are thus arranged by the key-bits, the cam-wheel F is turned by the key, and its arm k takes against the rear shoulder, o , on the bolt, and moves the bolt back until its stud passes through the openings f and into the openings g , and the tumblers, being now released, they disarrange themselves by means of their spring v . In this position the lock becomes a knob-catch or night-latch, as follows: By means of the knob

and its shank on the inside of the door the hub I and arm H can be operated to draw back the bolt, the bolt being shot out again by its spring x whenever it is released by letting go the knob; or the door may be pushed to, and the bevel on the bolt coming against the keeper pushes it into the lock until it has passed the bevel of the keeper, when its spring shoots it out again into the keeper. By inserting the key on the other side of the door, and turning it so that its bits shall arrange the openings c in line for the pin l on the arm k to enter, and then continuing to turn the key, the arm m on the cam-wheel F takes against the shoulder n of the bolt C, and moves back the bolt, and when the bolt is released by the removal of the key the tumblers disarrange themselves, and the lock, ceasing to be a night-latch, becomes again a knobbing catch bolt. The key can only be inserted and withdrawn when the cam-wheel F is in a certain position, and to keep it in that position the arm m is caught by a spring-latch, w, when the key is about to be withdrawn, and this

latch will hold the wheel in that position until the key is inserted and turned, which causes the arm to push back the latch and release itself.

Although I have described a peculiar kind of knob-shank and a knob upon one end only, yet I do not confine my invention to such solely, as an ordinary shank with a knob on both sides of the door may be used.

Having thus fully described the construction and operation of my combined lock, knobbing catch, and night-latch, what I claim therein as new, and desire to secure by Letters Patent, is—

In combination with a double-bited key, G, the cam-wheel F, tumblers E, and bolt C, constructed and operating together in the manner and for the purpose herein described and represented.

RANDOLPH S. FOSTER.
